LINOTYPE MACHINE ACCESSORY

Dexter B. Ellis, Ogden, Utah

Application May 28, 1940, Serial No. 337,716

11 Claims. (Cl. 199—56)

This invention relates to improvements in type-casting machines. It is particularly related to the casting and slug mold mechanisms of this type of machine, and the instant application disclosing its details is a continuation in part of an application for patent for Linotype machine accessory filed by Dexter B. Ellis, April 28, 1939, Serial No. 270,642. In the Mergenthaler Linotype and other typecasting machines of similar construction, a metal pot is moved at precise intervals to bring its outlet or mouthpiece into engagement with a typeslug mold. The face of the mouthpiece must be wiped clean of all surplus metal accumulations after each casting operation, otherwise a perfect fit of the mouthpiece against the mold will not be had at the moment when the molten metal is forced from the pot through the vents in the mouthpiece into the mold. If the aforesaid accurate fit is not maintained between the mold and the mouthpiece when the two are in the casting lock-up position, then the molten metal squirts out and imperfect type faces will result. This faulty operation necessitates extra hand labor for the removal of surplus metal from the face of the mouthpiece, obviously occasioning considerable loss of time and in many instances, damage to the face of the mouthpiece and mold.

It is common knowledge that the line-casting mold must be cooled after each slug is cast, otherwise the mold will become so hot that the constant inflow of high temperature metal will eventuate in a porous slug. When a slug of this type is subjected to the high pressure of a matrix 30 molding machine or platen press, the face and base of said slug often collapse. With this preamble in mind, the objects of the invention are as follows:

First, to provide an accessory for typecasting machines, specifically for the Mergenthaler Linotype machine, adapted to perform an automatic and simultaneous wiping of the mouthpiece of the metal pot and an air cooling of the mold after each casting operation.

Second, to provide an accessory of the foregoing character which is attachable without the necessity of drilling and tapping into or altering the existing machine, which derives its required motions from certain well-known moving parts of said machine and which will not interfere with the normal operation of any part of the machine referred to.

Third, to provide a combined wiper and cooler for the purposes stated, wherein the rectilinear movement of the pump plunger rod is the medium

for compelling a correspondingly rectilinear movement of the wiper blade across the mouthpiece.

Fourth, to provide a wiper-cooler which, while serving the dual purpose of wiping the mouthpiece and forcing cool air into the slug chamber, also acts as a cushion for the second elevator lever in its upward sweep towards its contacting position with the distributor box bar of a typecasting machine.

Other objects and advantages will appear in the following specification, reference being had to the accompanying drawings, in which:

Figure 1 is a side elevation of a portion of a typecasting machine, illustrating the application 15 of the invention.

Figure 2 is a detail plan view of a portion of said machine, particularly illustrating the association of the wiper with the metal pot and the mold carrier wheel.

Figure 3 is a front elevation of the mold wheel, illustrating the relationship thereto of the cooling and wiping devices.

Figure 4 is a perspective view of the combined wiper and cooler.

Figure 5 is a partially sectional and elevational view of the pump-wiper.

Figure 6 is a perspective view of the wiper blade guide.

Figure 7 is a detail perspective view of the combined wiper and cooler, the latter being seen from the rear.

Figure 8 is a detail perspective view of the wiper blade.

Figure 9 is a detail perspective view of the blade cover.

Figure 10 is a detail section taken substantially on the line 10—10 of Fig. 7.

Figure 11 is a detail cross-section taken on the line 11—11 of Fig. 1.

Figure 12 is a cross-section taken substantially on the line 12—12 of Fig. 2.

Figure 13 is a detail section taken substantially on the line 13—13 of Fig. 5.

Figure 14 is a cross section on the line 14—14 of Fig. 5.

Reference is first made to Fig. 1 wherein the main frame of a type-casting machine of a known construction is generally designated 1, a portion 3 of which is offset to define what is aptly called a shelf. The cam shaft bracket 2 provides the support for a cam shaft 4. This shaft is situated well within the interior of the machine, and it carries numerous cams from which the

various functions of the machine are derived, one of these cams being designated 5.

5 A lever 6, commonly known as the second elevator lever, is pivoted at 7 to a bracket 8 near the cam shaft 4. This lever has an arm 9 with a roller 10 that bears on the face of the cam 5. The rotation of the cam causes the periodic swinging of the lever 6 from the full to the dotted line position in Fig. 1 (arrow a), and this 10 motion of the second elevator lever is employed as the power source, so as speak, for the operation of the combined wiper and cooler.

The typecasting machine also includes a pot 11 which contains a quantity of molten metal 15 from which type slugs are cast. The arrangements for keeping the pot supplied with metal and for keeping the latter in the molten state are not disclosed because they do not relate to the invention. It is sufficient to note that the 20 metal pot 11 has a delivery-mouth 12 (Fig. 12) which terminates at the mouthpiece 13. This mouthpiece has a series of vents 14 (Fig. 3) through which the molten metal is expelled into the slug cavity 15 (Fig. 12) of a slug mold or 25 chamber 16 when the face 17 of said mouthpiece is moved into tight engagement with the mold 16. This action presupposes a periodic motion of the metal pot 11. This motion is derived from mechanism not shown, and it is sufficient 30 in extent to advance the pot far enough to bring the face 17 against the mold, as just stated, then to retract the mouthpiece to the approximate extent of the space 18 (Fig. 12).

The mold 16 as shown herein is one of a plurality of such molds carried by a wheel 19. This is a gear wheel, and the means and reasons for its periodic rotation are neither disclosed nor necessary to an understanding of the invention. It is customary in some constructions to make 40 the mold-carrier wheel hollow or jacketed as at 20 (Fig. 12) for the purpose of a water cooling system. It has been found through years of experience that the water cooling device is not effective for the reason that the water jacket 45 is too far removed from the slug mold 16 which the water is intended to cool. Thus an important part of the invention provides for introducing periodic charges of air directly into the slug mold cavity 15 (Fig. 3) after each slug has been cast 50 and ejected. The mold is stationed in the ejecting position in Fig. 3, at which time the slug chamber 15 is open to atmosphere making it possible to blow the air in and through and thus accomplish the cooling effect.

55 The importance of wiping the face 17 of the mouthpiece 13 clean has been pointed out. This function is accomplished by a wiper 27 (Fig. 4). This wiper is the first element of the invention, previously alluded to as the accessory, and it 60 consists of a blade 28 (Fig. 8) which is desirably made of flexible metal. At least one of the edges of the blade is serrated at 29. A cover 30 of felt, cloth or other desirable material is secured to the blade 28, the serrations 29 preventing the 65 cover from slipping off endwise or from rolling around the blade when the latter goes through its wiping action.

One end of the blade 28 is secured to an arm 70 31 which comprises an extension of the plunger rod 32. This rod works in a pump cylinder 33 through and beyond the ends of which it extends as substantially shown in Fig. 5. The rod 32 carries a plunger 34 which is operable in the cylinder 33 to produce the previously mentioned 75 charges of air. Said cylinder has one or more

air vents 39a (Fig. 4) at which outside air is admitted at the virtual limit of the plunger stroke in one direction. The plunger consists of a gasket 35 which is fitted between a pair of 5 holders 36. These, in turn, are held firmly in position by two beveled dowel pins 37 which are driven through holes in the plunger rod 32, and they have holes off-centered at 36a (Fig. 14) to secure an eccentric position of the rod in respect to the cylinder for a purpose later explained. 10

An opening 38 in the otherwise closed end of the cylinder 33 (Fig. 5) provides for the passage of the adjacent part of the plunger rod. The other end of the cylinder has a closure cap 39 which is secured to the threaded end of the 15 cylinder. This cap has a hole for the plunger rod. A nipple 40 on one side of the cap (Fig. 5) matches an opening 41 in the cylinder 33 and provides communication of the interior of the latter with an air tube 42 (Fig. 4) which leads 20 down to a position over the top of the slug ejector (not shown) directly over the slug mold cavity 15 (Fig. 3), and secured in this position by any suitable means to the main frame of the 25 machine.

A main supporting frame 44 carries most of the parts which comprise the accessory. This frame includes a bracket 45 (Fig. 5) to which the cylinder 33 is secured at 46. The bracket has an extension 47 which overlies the cap 39 as 30 well as a pair of air-retaining leather gaskets 48. These gaskets, as well as the extension 47, are perforated for the plunger rod, the free end of the extension having a screw 49 driven through it into the top of the air cylinder cap for the 35 purpose of holding the air cylinder rigid to the frame. The frame 44 is slotted at 50 (Fig. 7) to make room for an existing projection on the main frame of the machine 1. In the present instance, said projection consists of the nut and 40 bolt end shown in Fig. 1, and it may comprise the projecting end of a transfer lever spring hook in some types of this machine.

The frame 44 is curved and bent at 52 to conform to the previously mentioned shelf 3. The 45 frame is secured to portions of said shelf, for which purpose it has an arm 53 (Fig. 7) which is slotted at 54 for the purpose of adjustment in respect to a securing bolt 55 which goes through the slot into the distributor bracket of main 50 frame 1 (Fig. 1).

The bracket 47 terminates in a barrel 56 (Fig. 5) which is located crosswise of the bottom end of the cylinder 33. This barrel has registering slots 57 through which the plunger rod 32 passes 55 prior to its being bent into the arm extension 31. One end of the barrel is occupied by a spring 58 which abuts a hollow set screw 59 at one end and a plunger 60 at the other end. The plunger is kept pressed against one side of the plunger 60 rod, the other side of said rod thereby resting in the crotch 61 (Fig. 13) of a solid set screw 62 which is driven into the other end of the barrel.

The adjustments of the set screw 62 regulate the contact of the wiper 27 with the mouthpiece 65 13. If a closer contact is desired than is obtained by any particular setting of the screw 62, the rod 32 is simply deflected far enough to the left (Fig. 5) to release it from the crotch 61, whereupon the screw 62 is given one or more inward quarter turns to station the crotch that much farther inwardly of the barrel 56. The slight bending of the rod 32 does not interfere with its reciprocation.

A clevis 63 surmounts the upper end of the 75

plunger rod 32, being secured thereto in any desired way. The clevis has a cross pin 64 on which a roller 65 is mounted. This roller travels in a slot 66 in the adjacent end of an operating lever 67. This lever is pivoted on a bearing stud 68 which extends crosswise of an upstanding bracket 69. This bracket, although separate from the frame 44, is functionally a part thereof. Said bracket 69 has a slotted portion 70 which is secured, and adjustably so, to the frame 44 as at 71.

The bracket 69 is made somewhat in the nature of a fork. The portions 72 are brought into spaced and paralleled relationship to each other 15 so as to provide a passageway for the lever 67. One end of a spring 73 is anchored in this passageway, the other end of said spring being attached to a part of the lever 67. This lever has its main bearing on the stud 68 and the bearing 20 is made flexible so that it can yield in case the wiper rod, for any unforeseen reason, is stalled in its downward movement. In such an event the spring 73 will be expanded by the upward movement of the second elevator lever 6 and 25 allow this bearing to slide upward in the slot 69a, thus precluding any possibility of damage to the second elevator lever or the mouthpiece wiper blade. Said lever is offset at 74 at a place adjacent to the anchorage of the spring, and is 30 thereafter curved at 75 to provide a cam. The previously mentioned power of the second elevator lever 6 is transferred to the operating lever 67 on the upstroke of the former by means of a latch 76 (Fig. 11) that is carried by a clamp 77.

Said clamp comprises a block 78 to which the latch 76 is pivoted at 79. The block is attached to one of a pair of clamp halves 80 and 81 which are applied to the opposite sides of the lever 6. Said halves are connected by bolts 82, the actual 40 fastening of the clamp to the lever 6 being accomplished by a pair of divergently positioned set screws 83 which are driven against the approximate outside corners of the lever 6.

When the second elevator lever 6 is raised 45 (arrow a, Fig. 1) the latch 76 comes into engagement with the nether side of the cam 75. The latch then rides against the cam, and in doing so, swings the operating lever 67 on its pivot, thus to simultaneously drive the pump plunger 34 downwards and sweep the wiper 27 across the mouthpiece 13. In order to stabilize this sweeping motion of the wiper, provision is made of a guide 84 (Fig. 6), this guide comprising 50 an arrangement of clamp plates 85 and 86 which are secured by means of bolts 87 to what is known in the existing machine as the mold wheel supporting bracket 88 (Fig. 3). This bracket is so situated that it conveniently supports the guide 84 closely adjacent to the mouthpiece 13. The guiding function is derived from a relatively tall plate 89, one edge of which is beveled at 90 to coat with the exposed tip 91 of the wiper blade 28. When the blade makes a 55 down stroke, said tip engages the bevel 90, which is located on that side of the plate 89 nearest the mouthpiece 13, causing the wiper to move in a rectilinear path directly across the mouthpiece and without bending outwardly therefrom.

The operation

is readily understood. The second elevator lever 6 swings up and down periodically and performs its functions in the known typecasting machine, 75 and as it does, the metal pot 11 is stepped back

from the mold carrier wheel 19 for the dislodgement of the previously cast type slug from the slug chamber 15 by action of the ejector blade (not shown). It is at this period of the operation of the typecasting machine that the space 5 18 (Fig. 12) becomes evident, and it is at this moment that the invention performs its part in simultaneously wiping the mouthpiece 13 and causing a circulation of air through the slug chamber 15 for the purpose of cooling the walls 10 of the latter.

It is the second elevator lever 6 which is responsible for this performance. The power derived from its upward motion causes the swinging of the operating lever 67 (dotted lines, Fig. 1). The spring 73 is stretched by this swinging. The actions of the wiper 27 and pump plunger 34 are performed simultaneously because they are commonly carried by the plunger rod 32. The downstroke of the plunger 34 is responded to by a downstroke of the wiper 27. When the plunger is forced downward it passes beyond the air vents, allowing cool air to enter the air compression cylinder, and when the plunger is moved upward by action of the spring 73, it passes these air vents and forces the air entrapped ahead of it through tube 42 into the slug chamber 15, at the same time moving the wiper 27 upwardly across the mouthpiece 13. 20 These acts occur after every revolution of the mold wheel 19 and when the mold 16 thereof stops at the ejecting position (Fig. 3), at which time cool air is forced directly into the slug mold cavity, cooling the top, bottom and both sides 25 of the entire mold. It is important to note that the cooling part of this accessory cools only the mold that is being used to cast type slugs. 30

It is also important to note that the motions of the wiper 27 are rectilinear. This desirable function is a main contribution of the plunger 34 40 because its movement over the internal wall of the cylinder 33 performs a guiding action. The latter is supplemented by the wiper blade guide 84 (Fig. 6), with which the blade tip 91 engages so as to guard against any deviation of the wiper 45 from its plane of movement.

Reverting to the eccentricity of the plunger rod 32 (Fig. 14), the reason for this provision in respect to the cylinder 33 is that there is so little space between the main frame of the machine and the metal pot jacket that an air cylinder with sufficient air capacity to efficiently cool the mold cannot be accommodated if the holes in the plunger were centered, and allow the operating rod to clear the pot jacket and the line delivery lever. In other words, the air cylinder must be crowded against the frame of the machine and the cylinder cap milled off on the right-hand side to give the operating lever space to clear the upper portion of the mouthpiece in its upward 50 and downward movement. In this operation the mouthpiece wiper operating rod has less than one five-hundredth of an inch clearance. So the wiper rod must be crowded over as close as possible to the right-hand side of the air cylinder, making the gasket holders eccentric in position and the holes in them off-center. 55

The latch 75 functions as follows: when the second elevator lever 6 descends from its position at the distributor box bar (not shown) to contact the intermediate line transfer channel, it depresses this latch and allows the latch to go under the operating lever 67, and when the second elevator 6 starts its upward movement the latch contacts the cam 75 and rides therealong, 70 75

propelling wiper rod 32 downward and causing the mouthpiece wiper blade to pass over the face of the mouthpiece.

5 The coil spring 73 brings the wiper blade back to its normal position above the pot mouthpiece. The latch 76 loses contact with the cam 75 when the second elevator lever is about three-fourths the distance in its upward movement to contact the distributor box bar.

10 I claim:

1. A typecasting machine having a mold with a slug chamber, a metal pot periodically retractable from the mold so as to space its mouthpiece from the mold, and an elevator lever partaking 15 of a swinging motion during said period of retraction; in combination a pump cylinder, a plunger operable in the cylinder, an air tube leading down from the air cylinder to the rear of the slug chamber, a wiper to wipe the mouthpiece, a rod commonly carrying the plunger and wiper so that the wiper moves rectilinearly in 20 consonance with the plunger, and means operated by the motion of said lever to actuate said rod to cause an air flow through said chamber simultaneously with a wiping action of said wiper across the mouthpiece.

2. A typecasting machine having a mold with a slug chamber, a metal pot periodically retractable from the mold so as to space its mouthpiece from the mold, and an elevator lever partaking 30 of a swinging motion during said period of retraction; in combination, a pump cylinder, an air tube providing air communication of the cylinder with the interior of the slug chamber, 35 a wiper to wipe the mouthpiece, a rod commonly carrying the plunger and wiper, said rod supporting the wiper in position at one side of the mouthpiece, and means operated by the motion of said lever to actuate the plunger rod in one direction to simultaneously displace the plunger and wiper in the same direction, thereby to cause 40 an air flow into and through said chamber and a wiping action of the wiper across the mouthpiece.

45 3. A typecasting machine having a mold with a slug chamber, a metal pot periodically retractable from the mold so as to space its mouthpiece from the mold, and an elevator lever partaking 50 of a swinging motion during said period of retraction; in combination, a pump cylinder, an air tube providing air communication of the cylinder with the interior of the slug chamber, a wiper to wipe the mouthpiece, a rod commonly carrying the plunger and 55 wiper, said rod supporting the wiper in position at one side of the mouthpiece, means operated by the motion of said lever to actuate the plunger rod in one direction to simultaneously displace the plunger and wiper in the same direction, thereby to cause 60 a wiping action of the wiper across said mouthpiece, and means put under tension by said motion of the lever, actuating the plunger rod independently of said lever and in the opposite direction to cause an air flow through said chamber and a reverse wiping action.

65 4. A typecasting machine having a mold with a slug chamber, a metal pot periodically retractable from the mold so as to space its mouthpiece from the mold, and an elevator lever partaking 70 of a swinging motion during said period of retraction; in combination, air pumping means in communication with the slug chamber and having a reciprocable part for producing an air current through said chamber, wiper means supported by said reciprocable part in line with the

mouthpiece but spaced away therefrom, an operating lever coupled to the pumping means thereby to impart motion to its reciprocable part and to the wiper means, and a member attached to the elevator lever, adapted to engage said 5 operating lever for the transfer of motion.

5. A typecasting machine having a mold with a slug chamber, a metal pot periodically retractable from the mold so as to space its mouthpiece from the mold, and an elevator lever partaking 10 of a swinging motion during said period of retraction; in combination, a pump cylinder, a plunger operable in the cylinder, an air tube providing air communication of the cylinder with the slug chamber, a wiper to wipe the mouthpiece, a 15 rod commonly carrying the plunger and wiper so that the wiper moves in consonance with the plunger, means operated by the motion of said lever to actuate said rod to cause an air flow through said chamber simultaneously with a wiping action of said wiper, and guide means stationed contiguously to said mouthpiece to guide said wiper in a rectilinear path across and in contact with said mouthpiece.

6. An accessory for a typecasting machine 25 comprising a pump cylinder, a plunger operable in the cylinder, an air tube leading from the cylinder for the passage of an air current to a slug chamber, a wiper to traverse the mouthpiece of a metal pot, a rod commonly carrying the plunger 30 and wiper, and an operating lever coupled to the plunger rod for producing simultaneous air currents and wiping actions upon at least one stroke of said rod imparted thereto by the operating lever.

7. A typecasting machine having a mold with a slug chamber, a metal pot periodically retractable from the mold so as to space its mouthpiece from the mold, and an elevator lever partaking 40 of a swinging motion during said period of retraction; in combination, a pump cylinder, a plunger operable in the cylinder, an air tube providing air communication of the cylinder with the slug chamber, a wiper to wipe the mouthpiece, a rod commonly carrying the plunger and 45 wiper so that the wiper moves in consonance with the plunger, means operated by the motion of said lever to actuate said rod to cause an air flow through said chamber simultaneously with a wiping action of said wiper, and means acting 50 against the plunger rod, serving to adjustably hold the wiper to a determined line of movement across the face of the mouthpiece.

8. A typecasting machine having a mold with a slug chamber, a metal pot periodically retractable from the mold so as to space its mouthpiece from the mold, and an elevator lever partaking 55 of a swinging motion during said period of retraction; in combination, a pump cylinder, a plunger operable in the cylinder, an air tube 60 providing air communication of the cylinder with the slug chamber, a wiper to wipe the mouthpiece, a rod commonly carrying the plunger and wiper so that the wiper moves in consonance with the plunger, means operated by the motion of 65 said lever to actuate said rod to cause an air flow through said chamber simultaneously with a wiping action of said wiper, and means guiding the plunger rod, being adjustable in respect to said rod to guide the rod along selected paths and thus 70 hold the wiper to a corresponding line of movement across the face of the mouthpiece.

9. A typecasting machine having a mold with a slug chamber, a metal pot periodically retractable from the mold so as to space its mouthpiece 75

from the mold, and an elevator lever partaking of a swinging motion during said period of retraction; in combination, a pump cylinder, a plunger operable in the cylinder, an air tube providing air communication of the cylinder with the slug chamber, a wiper to wipe the mouth-piece, a rod commonly carrying the plunger and wiper so that the wiper moves in consonance with the plunger, means operated by the motion of said lever to actuate said rod to cause an air flow through said chamber simultaneously with a wiping action of said wiper, an element guiding the plunger rod, said element being adjustable to direct the rod along any one of several paths and thus to hold the wiper to a corresponding line of movement, and resilient means acting against the rod to slidably hold the rod against said element.

10. An accessory for a typecasting machine comprising a main supporting frame securable to the frame of said machine, air jet discharging means mounted on the frame, a plunger forming part of said means, including a rod extending

from said means and terminating in a mouth-piece wiper blade, and an operating lever movably mounted on said supporting frame, having a coupling at one end to said plunger rod and having a formation at the other end adapted to be engaged by an actuating member, thereby to simultaneously actuate the air jet means and mouth-piece wiper. 5

11. An accessory for a typecasting machine comprising a main supporting frame securable to the frame of said machine, a bracket comprising part of said supporting frame and terminating in a barrel, a reciprocable plunger rod extending through the barrel and terminating in a wiper blade, an operating lever movably mounted on said supporting frame, having one end coupled to the plunger rod and the other end adapted to be engaged by an actuating member, adjustable means in the barrel having a crotch in which the rod is slidable, and resilient means also in the barrel, exerting pressure against the rod to keep it in said crotch. 10 15 20

DEXTER B. ELLIS.
